DOOR OPERATING MECHANISM

Paris E. Forman and Roscoe D. Conklin, Rahway,
N. J., assignors to National Pneumatic Com-
pany, New York, N. Y., a corporation of West
Virginia

Application April 29, 1939, Serial No. 270,727

3 Claims. (Cl. 268—65)

This invention relates to improvements in power operated door mechanisms.

An object of this invention is to provide, in combination with a door or similar closure member, and a door check device arranged to close the door, a motive device for supplying the power to open the door and means interconnecting it with the door whereby the motive device opens the door and the door check device is free to and does close the door.

Another object of this invention is to provide, in a combination of the above type, a member driven by the motive device for causing the door to open and immediately returnable from open position after the door reaches fully open position, either by the motive device or independently thereof.

Another object successfully secured by the above mechanism is that of being able to manually open the door independently of the power operating mechanism whereby the failure thereof does not prevent the normal use of the door.

An additional object of the invention successfully secured by the above mechanism is that of permitting the door to be held open after being opened by the mechanism without disturbing it structurally or functionally and without any special action on the part of the user.

Additional objects of this invention which are successfully secured thereby will be apparent to those skilled in the art in view of the following detailed description of two forms of the invention submitted for the purpose of illustrating the true scope thereof.

This invention resides substantially in the combination, construction, arrangement and relative location of parts as hereinafter disclosed.

In the accompanying drawings,

Figure 1 is a front elevational view of the upper portion of a closure member and the mechanism associated therewith which, in combination, comprises one form of this invention.

Figure 2 is a detailed cross-sectional view taken on the line 2—2 of Figure 1.

Figure 3 is a left hand end elevational view of a detail.

Figure 4 is a diagrammatic illustration of a suitable circuit for this mechanism.

Figure 5 is a view similar to that of Figure 1 with the closure member omitted, showing a modified form of this invention.

Figure 6 is a diagrammatic illustration of a suitable circuit for the modified form of the invention.

In the structure of Figures 1 to 4 inclusive, a member which may be termed herein a nut, when moved by the power source in one direction, causes through suitable connecting means the closure member to open and as soon as it is fully open the nut is returned to its initial position independently of the motive device. This leaves the door free to be closed by means of a door check device which may take any one of a number of known forms.

As illustrated in Figure 1, the wall or framework containing the door opening is indicated by the reference numeral 1. The door which closes this opening is shown at 2 mounted at the side of the opening by a plurality of hinges 2', only one of which is shown so that the door is of the swinging type.

Mounted on the door near the top, at any suitable location, is a door check device 3 which is illustrated in one well known form. The check device is secured to the door as illustrated by means of a bracket 4 which is integral with the housing of the check device and secured to the door in any suitable manner. This check device, as is well known, comprises a casing having a vertical shaft rotatably mounted therein which is provided, as shown, with an arm or lever 5 extending horizontally. The lever 5 is pivotally connected at 6 to a lever 7 which in turn is pivotally connected at 8 to an attaching plate 9 secured in any suitable manner to the wall in which the door opening lies.

Door check devices of this type are usually provided with a spring, as is well known, which stores potential energy when the door is open which is expended in closing the door when free. In addition these devices are normally provided with some form of cushioning mechanism such as dashpots to ensure a smoother action.

At 10 is a supporting plate of any suitable form which is secured to the wall over the door opening and is adapted to receive, as is clear from Figure 2, a removable cover 11 by means of which the mechanism is enclosed. In the bottom wall of the cover there is provided a longitudinal slot 12 as is clear from Figure 2, for a purpose to be explained later.

Mounted on the base 10 is a motive device 50 which in the form of the invention illustrated is an electric motor. It will be apparent as the description proceeds that other suitable forms of motive devices can be used, as for example a pressure fluid operated engine with the necessary mechanism to convert its rectilinear movement

to rotational movement. As illustrated the electric motor 13 is provided with a pulley 15 attached to its shaft 14. This pulley is connected by a belt 16 to a pulley 31 which is attached to the shaft 18. Adjacent thereto is an open ended annular housing 17 through which the shaft 18 passes freely. The housing 31 is attached to the adjacent standard 19 of a pair of standards 19 and 20 mounted on the plate 10. The threaded rod 18 is rotatably mounted in these brackets. This rod has mounted on the end thereof adjacent the housing 17 a sleeve 22 which is connected to the inner end of a spiral spring 21 by means of a rivet or screw 23. The outer end of the spring 21 is connected to the wall of the member 17 by means of a rivet or screw 24. As is clear from Figure 2, this spirally wound spring is enclosed within the annular housing 17. Extending between the standards 19 and 20 is a pair of parallel rods or guide bars 25 and 26 which lie parallel to the screw rod 18. A carriage 27 provided with suitably shaped sleeves 28 and 29 slides on the rods 25 and 26. The carriage is provided with a central passage therethrough, as is clear from Figures 1 and 2, of a diameter so that the threaded rod 18 may pass freely through it. A member 30 is slidably mounted on the rods 25 and 26 and has a central threaded passage which engages the threads on the rod 18 and may therefore be termed a nut.

Secured to the housing of the door check 3 is a bracket 33 to which at one end is pivotally connected a link 32 which is also pivotally connected at its other end to a depending projection on the carriage 27. Mounted on the base 10 is a limit switch 35 provided with an operating arm 34 positioned to be engaged by a lug 33 mounted on the carriage as will be explained later. In Figure 1 there is diagrammatically illustrated at R a relay which will be referred to in connection with Figure 4.

In Figure 4 the terminals 36 and 37 of the circuit are adapted to be connected to any suitable current source. The lead 39 from the terminal 36 has connected therein the limit switch 35. Lead 39 is connected to a wire 40 which terminates at one end in a pair of spaced contacts 41 and at the other end in a fixed contact 42 forming part of the relay R. Another part of contacts 43 positioned adjacent the contacts 41 is connected by the wire 44 to one terminal of the operating winding 45 of the relay R. The other terminal of the winding is connected by wire 46 to one terminal of the motor 13. The other terminal of the motor is connected by wire 49 to wire 44 and by wire 50 to the fixed terminal 51 of the relay. Wire 46 is connected by wire 47 to the terminal 37. The relay is provided with a movable contact 52 which is out of engagement with the fixed contacts 51 and 42 when the winding 45 is deenergized and in engagement therewith when energized. The pairs of contacts 41 and 43 are part of push button switches which have been designated by the reference characters O and C. These push button switches are mounted on the wall 1 adjacent the door on opposite sides thereof and serve to initiate the opening operation when operated respectively by a person desiring to move through the door opening.

The operation of the device will now be described in detail, it being assumed that the door is closed, terminals 36 and 37 are connected to a suitable current source and switches O and C are open. At this time the limit switch 35 is closed

and relay R is deenergized. In order to open the door from either side either switch O or C is manually operated thereby connecting the respective contacts of the pairs 41 and 43 together.

Current then flows from the source to terminal 36 through closed limit switch 35, wire 39, wire 40, the connected pair of contacts 41 and 43, wire 44, winding 45, wire 46, and back to the current source through wires 47 and terminal 37. This energizes the winding 45 and operates the relay so that movable contact 52 interconnects the contacts 51 and 42. Current then flows from the wire 40 through contact 42, movable contact 52, contact 51, wire 50, wire 49, winding 45, wire 46, and wire 47 providing a holding circuit for the winding 45 maintaining it energized.

Current also flows from wire 50 through the motor 13 and back to the current source through wires 46 and 47. Thus the motor is energized causing it to revolve with the result that the shaft 18 revolves and at the same time the spring 21 winds up. The threads on the shaft 18 and the nut 30 are in the proper direction to cause the nut 30 to move from its initial position shown in Figure 1 towards the right. As it moves, it causes carriage 27 to slide to the right.

Through the connecting mechanism the door is caused to swing open. At this time it may be noted that the slot 12 in the cover 11 is provided so that the depending projection on the carriage may move therein. As the door reaches fully open position, the lug 33 on the carriage 27 engages the operating arm 34 of the limit switch 35 to open it. It may be noted that the spiral spring 21 is not tightly coiled so that any tendency of the motor to overrun at this time can be absorbed by the spring.

As soon as limit switch 35 opens winding 45 of the relay is deenergized so that the holding circuit for the winding and the current supply circuit for the motor are broken by the disengagement of contact 52 and contacts 51 and 42. At this point it may be noted, as is obvious, that switches O and C need only be closed momentarily in view of the fact that a holding circuit is set up for the relay. When the motor circuit is broken it is quickly brought to a stop by the further coiling of the spring 21. Immediately thereupon the coiled spring 21 causes the shaft 18 to revolve in the reverse direction returning the nut 30 to its initial position. The springs 36 and 37 on the rods 25 and 26 serve as bumpers to aid in bringing the nut to a stop. When the nut is back at its normal position the coiled spring 21 is relaxed to its normal position as shown in Figure 3. Also it is capable of additional uncoiling movement if necessary. In other words, in all normal operation of this apparatus the spring 21 is never coiled or uncoiled to the maximum.

The return of the nut 30 leaves the door free to be returned to closed position by means of the door check device which as is well known is a motive device which stores energy on the opening of the door sufficient to close the door when it is released. As the door is returned to closed position the carriage 27 is caused to slide back to its initial position. With this arrangement it will be seen that the door is not positively connected to the drive mechanism so that it can be freely opened by hand and when fully opened can be held open as long as may be desired.

In Figures 5 and 6 many of the parts are the same as before and where this occurs the same reference numerals are employed. It may be

noted that the link 32 is connected to the door check as before, which is mounted on the door and secured to the door frame as previously described. The main difference between the structure here disclosed and that previously described is that the casing 17 and the spring mechanism therein is omitted and in place thereof there is provided a pulley 17' rigidly secured to the shaft 18. This pulley is connected by the belt 16 to the pulley 15 as before. The carriage and nut structure are the same. However, another limit switch 60 is provided, with an operating arm 61 arranged to be engaged by the lug 33 when the door is in closed position to open switch 60.

In this case the relay R' is provided with many more movable contacts than in the previous case and the motor 13' is a reversing motor. The current supply terminal 36 is connected by wire 38 to one terminal of the winding 45 of the relay and to two contacts of a fixed pair controlled by the relay. One contact of another pair is connected by wire 70 to one of the fixed contacts of the push button switch 71. The other terminal of the push button switch is connected by wire 72 to the current supply terminal 37 and through the limit switches 35 and 60 to the corresponding contacts of three pairs controlled by the relay.

The other terminal of the winding 45 is connected to the wire 70. Wire 38 is connected by wire 62 to one of the windings of the motor 13', the other terminal of that winding being connected to one of the contacts of each of four pairs controlled by the relay. One of the contacts of each of two pairs of the relay is connected by wire 80 to one terminal of another winding of the motor 13' and the remaining terminal thereof is connected to one of the fixed contacts of each of another pair controlled by the relay. The relay is provided with seven movable contacts designated by the reference numerals 73, 74, 75, 76, 77, 78 and 79. The movable contacts 73, 74, 75 and 76 cooperate with four pairs of the fixed contacts and are out of engagement therewith when the winding 45 is de-energized, as shown. At this time the movable contacts 77, 78 and 79 interconnect three pairs of the fixed contacts of the relay. Only one push button switch 71 is shown but it is apparent that as many more as desired may be connected in parallel therewith so that the door may be opened from either side or from any desired point.

In the operation of this arrangement, when switch 71 is closed current flows from terminal 36 through wire 38, winding 45, wire 70, closed switch 71, and back to the current terminal 37 through wire 72, energizing winding 45. The movable contacts of the relay then shift from the position shown to the other position so that the circuits through the lower three contacts are broken and the circuits through the upper three contacts are made. Current then flows through wire 38, winding 45, wire 70, the switch including the movable contact 73, closed limit switch 35, and back through wire 72 to the terminal 37. Thus a holding circuit for the winding 45 is completed and therefore switch 71 need only be closed momentarily. Current also flows from wire 38 through the closed switch including the movable contact 76 through wire 81, the winding of the motor connected thereto, wire 80, the switch including the movable contact 75, through the wire connected thereto, to the switch including the movable contact 74 and through the closed limit switch 35 to wire 72.

Current also flows from wire 38 through wire 73

82, the winding of the motor connected thereto and wire from its other terminal to the switch including the movable contact 74 and through the closed limit switch 35 to wire 72. Thus the motor is energized in a direction to cause the nut 30 to be advanced towards the right hand end of the mechanism causing the door to open as before. Just as the door is fully open the arm 33 engages the operating member 34 of switch 35 opening it.

It will be remembered that as soon as the carriage 27 began to move, arm 34 released the operating member 61 of the limit switch 60 so that it closes. The closing of this switch, of course, does not affect the circuits since the switch of the relay including the contact 71 is at this time open. As soon as limit switch 35 opens, the holding circuit for the winding 45 is broken and the relay returns to the position shown in Figure 6.

The connections for the motor 13' are now reversed with the closing of switch 60 and the switch containing the contact 79, the lower winding of the motor is energized in the same direction. However, the upper winding of the motor is energized in the reverse direction. In this case current flows from wire 38 through switch including contact 71 to wire 80 and through it to the connected terminal of that winding. It will be remembered that before the wire 38 was connected to the other terminal of the winding.

Continuing this case, however, current flows from this winding back through wire 81 through the switch containing the movable contact 78 to the wire connected thereto, through the switch containing the contact 79 and limit switch 80 back to wire 72. Thus one winding of the motor 13' is reversed and the motor is energized for operation in the reverse direction. This causes the shaft 18 to revolve in the opposite direction, carrying the nut back with it to its initial position. As the nut gets back to its initial position limit switch 60 opens—it will be remembered that previously limit switch 35 has closed. This leaves the carriage free so that the door can be closed by the door check motor or held open as long as desired. At this time the circuits are returned to normal position, that is, the position shown in Figure 6 and the device is ready for operation to again open the door.

From the above description it will be apparent to those skilled in the art that the features of this invention may be embodied in other physical forms. We do not, therefore, desire to be strictly limited to the description as given for purposes of illustration herein, but rather to the scope of the appended claims.

What we seek to secure by United States Letters Patent is:

1. In a combination as described, a framework forming a door opening, a door movably mounted in the opening, a motive device interconnecting the door with the framework for closing the door, a motor supported on the framework, a screw supported for rotation on its longitudinal axis, means for connecting said motor to said shaft to rotate it, a spring interconnecting said screw with a fixed support, means forming a guideway, a nut mounted on said guideway and engaging said screw, a carriage mounted on said guideway so as to be engaged by said nut, and a connection between said carriage and said door whereby said motor causes movement of the nut along the guideway to cause movement of said carriage

in one direction to open the door and energizes said spring so that when said motor is de-energized said spring operates said screw to return the nut to initial position so as to free said carriage, so that said motive device is free to close the door.

2. In a door operating combination a door, motive means connected to the door and biasing it to closed position, a threaded shaft journaled adjacent the door, a motor, driving connections between the motor and shaft, a spring connected at one end to the shaft and at the other to an adjacent part, a driver engaging the threaded shaft and moved by rotation thereof, and means engageable by the driver and connected to the door whereby the motor when energized causes the door to open and said spring energized to quickly

return the driver to door closed position when the motor is de-energized so that said motive device is free to close the door.

3. In a mechanism as described a door, a threaded shaft journaled for rotation, a motor, driving connections between said motor and shaft, a spring connected to said shaft so as to be tensioned when the motor is energized, driving means engaging the threads of said shaft so as to be movable thereby, means independent of said shaft and connected to the door for opening the door when said driving means moves and biasing means for closing the door, said driving means being quickly returned to door closed position by 10 said spring when the motor is de-energized.

PARIS R. FORMAN,
ROSCOE D. CONKLIN.
